UNITED STATES PATENT OFFICE.

CHARLES D. MOSHER, OF NEW YORK, N. Y.

AIR-HEATING APPLIANCE.

1,364,135.

Specification of Letters Patent. Patented Jan. 4, 1921.

Application filed October 6, 1917. Serial No. 195,033.

To all whom it may concern:

Be it known that I, CHARLES D. MOSHER, a citizen of the United States, residing at New York city, in the county of New York and State of New York, have invented certain new and useful Improvements in Air-Heating Appliances, of which the following is a specification, reference being had therein to the accompanying drawing.

- 10 My invention relates to improvements in means combined with the boiler and furnace of a steam generating plant for heating the air by the products of combustion as the same is supplied to the furnace.
- 15 Referring to the accompanying drawings. Figure 1 illustrates in side elevation, partly in section and with parts broken away, a suitable outline of a steam generating plant, illustrating an application of my invention.
- 20 Fig. 2 is an enlarged perspective view partly in section and parts broken away, illustrating the chamber through which the air supplied for combustion is heated by the waste gases on their way to the flue, and Fig. 3
- 25 is an enlarged plan view looking down upon the air heating chamber with the upper part removed.

4 indicates a conventional form of tubular boiler, and 5 the furnace beneath the 30 same from which the gases pass rearwardly over the bridge wall 6, in through the back of the boiler 7 and out of the front 8 into the uptake 9.

When starting the fire the damper 10 is 35 preferably opened or lifted from the flue 12 as shown in dotted outline, the same being provided with a suitable counterweight 11. This allows the smoke and gases from the fresh fire to pass downwardly through the 40 flue 12, beneath which the soot and carbon are deposited as indicated at 13, the gases continuing beyond the damper 14 which swings open under the influence of the draft augmented by the blower 33 allowing the 45 gases to pass upwardly through the smoke-stack 15, 16 indicating a suitable door for cleaning and repairs. After the fire has blown up sufficiently, the damper 10 may be closed or dropped down upon the flue 12, 50 and the grid 17 provided with a counterweight 18 may be opened as shown in dotted outline. This grid 17 consists preferably of a series of steam pipes 19 (referring to Fig. 3) provided with holes such as 20 through 55 which steam may be blown down through the air heater shown in Fig. 2 for cleaning

the same when the grid is down. The steam pipes 19 are provided with suitable caps such as 21 and at their other ends are connected to the header 22 receiving steam from the pipe 23 as shown in Fig. 1 a suitable counterweight such as 18 being provided to hold the pipe 19 or grid in opened or closed position, the same serving when closed down, as a damper. This grid is shown 60 open in dotted outline in Fig. 1 and closed in Fig. 3.

Referring now more particularly to Fig. 2, it will be observed that the air heating chamber therein shown is connected at the top with the flue 9 from which the products of combustion having passed through the boiler, pass downwardly between the corrugated plates 25 of the air heater. In other words, a series of crinkled or corrugated 70 plates such as 25 are mounted in parallel arrangement on ends between the walls of the air heater as shown, alternate spaces between the tops of said corrugated plates being closed as indicated at 26 thus allowing 75 the furnace products to pass only through every other space such as indicated by the reference character 27, thus providing for a passage for the hot gases on both sides of each of the air passages. These products of 80 combustion escape through the spaces 27' at the bottom of the air heater and pass through the base flue or duct 28 to the stack 15. In addition to the side walls such as 29 85 of the air heater, suitable fillers or separators such as 30 may be employed between the corrugated plates for closing the spaces 90 at the sides between them.

The alternate fillers 30 are also preferably cut away at the top and bottom as indicated to allow the air from the blower 33' to pass through the openings 31 between the plates of the air heater as aforesaid to the duct 32' by way of the air flue 34 which conveys the heated air beneath the furnace fire, this air having passed in at the bottom of the air heater through the openings 31 from the blower 33'. In this way the incoming fresh air is thoroughly heated by the products of 100 combustion passing through the air heater 105 in the opposite direction.

What is known as stratification of gases forms a strong barrier to prevent the transfer of heat from a gas on one side of a plate to a gas or air on the other side of the plate. 110 That is, a gas will flow along a straight surface and closely adhere to that surface thus

heating only a thin stratum of the air or gas which forms an excellent insulator thereby preventing the heat from being transferred to the adjoining strata or mass of air which passes by without receiving much heat and this accounts for the very poor efficiency of air heaters in general. To avoid such action, I have provided for the outgoing hot gases or products of combustion and the incoming cool air, an arrangement providing for a counterflow of the gases and air, that is to say, I have provided for the products of combustion to flow through the air heater in a direction opposite to that in which the air flows through to as to bring the hottest gases in contact with the air as it leaves the air heater, thereby heating it as nearly as possible to the temperature of the hot gases as they leave the furnace. This is further accelerated by the action of the corrugated or crinkled walls or passages as it will be seen that these corrugations cause the air and gases to constantly change their direction of flow as they pass each corrugation causing both air and gas to impinge against the next corrugation at an angle of perhaps preferably from thirty to forty-five degrees, the air on one side of the corrugated plate impinging at a point practically opposite to where the hot gases impinge against the opposite side of the same plate, thus breaking up stratification and causing a very much larger amount of heat to be transferred from the products of combustion to the air per unit of surface than is possible when the passages are straight such as when made up from flat plates.

From the foregoing it will be seen that an enlarged heating surface is presented to the products of combustion as the same escape to the uptake or flue 15, the corrugated walls causing the particles of air and gases to rebound back and forth from corrugation to corrugation as they pass therethrough causing different particles to constantly contact with the corrugated surfaces until the temperatures become more or less uniform.

For the purpose of removing any particles of accumulated dust or soot upon the corrugated walls, the steam tubes 19 may be dropped down in the position shown in Fig. 3 and the steam may be turned on by the valve 23', thus driving any accumulated dust down into the dust pocket 13, or the grid of tubes 17 may be dropped down into position without turning on the valve 23', thereby serving to close off the air heater

when the damper 10 is opened, such as when 60 a fresh fire is being started.

The foregoing arrangement provides convenient, practical and accessible construction, not only for pre-heating the air supplied to the furnace, but for doing so efficiently by utilizing the heat otherwise lost in the waste gases from the furnace, at the same time, providing a more direct escape for the products of combustion when the fire is being started, and at the same time, 70 providing convenient and accessible means for cleaning out the air heater, and for removing the dust and soot from the flues.

Of course any suitable form of blower may be provided for establishing any necessary draft, and various other modifications may be made in the construction and arrangement of the parts without departing from the spirit of the invention as claimed.

I claim:

1. In combination with a furnace, an air heater through which air supplied to said furnace is passed, said air heater comprising a substantially parallel arrangement of irregular sheets providing passages for said air and alternately therewith providing passages for the escape of furnace gases, said furnace gases passing directly through said passages from end to end, means for admitting the air in a direction opposite to the direction of said gases, and in combination therewith means for collecting the deposits from said chambers through which said furnace gases pass.

2. In combination with a furnace, an air heater through which the products of combustion may be passed, a by-pass for said products of combustion, means for passing said products of combustion through said air heater or through said by-pass, and means in combination with said air heater for blowing out the dust from said furnace gases.

3. In combination with a furnace and an air heater for receiving the products of combustion therefrom and for supplying air thereto, a by-pass for the products of combustion between said air heater and said furnace, and means in combination with said by-pass for controlling the products 110 of combustion passing therethrough.

In testimony whereof I hereunto affix my signature in the presence of two witnesses.

CHARLES D. MOSHER.

Witnesses:
